UNITED STATES PATENT OFFICE.

THOMAS F. MARTIN, OF NEWBURG, NEW YORK, ASSIGNOR TO HIMSELF AND JOHN C. ADAMS, OF SAME PLACE, AND M. S. FROST & SON, OF NEW YORK, N. Y.

GAS-MAKING APPARATUS.

SPECIFICATION forming part of Letters Patent No. 320,078, dated June 16, 1885.

Application filed March 16, 1885. (No model.)

To all whom it may concern:

Be it known that I, THOMAS F. MARTIN, of Newburg, in the county of Orange and State New York, have invented an Improvement in 5 Gas-Making Apparatus, of which the following is a specification.

Gas-making apparatus has before been constructed in which steam is passed into a retort containing incandescent fuel, so that said 10 steam is decomposed and the resulting gases pass into a superheater together with vaporized petroleum and the hydrogen of the steam and the olefiant gas of the petroleum are mixed and combined. In this character 15 of gas-making apparatus the petroleum is liable to form lamp-black in consequence of the excessive heat to which it is exposed, and the bed of incandescent fuel upon which such petroleum runs is chilled and requires to be 20 reheated at frequent intervals.

The object of my improvement is to avoid the formation of lamp-black and to conserve the heat of the incandescent bed of fuel by relieving it of the work of vaporizing other 25 hydrocarbon, and vaporizing it at another point and in another manner, as hereinafter set forth. I also construct the superheater with a bridge-wall between the body of the superheater and the escape flue or chimney 30 so that when the apparatus is being heated up the heat will be retained and act to better advantage than in the superheater as heretofore made, and I provide within the casing that incloses the superheater a descending-flue to connect the horizontal flue of the generator with the bottom of the superheater, and thereby retain the heat in the descending-flue, so that it aids in elevating the temperature 35 of the superheater.

In the drawings, Figure 1 is a vertical section of the apparatus, and Fig. 2 is a sectional plan view at the line *xx*.

The generator A is made with a fire-brick lining inside a metallic casing, as usual, and 45 there is a grate, *a*, upon which is supported the fuel.

B is a removable cover at which fuel can be inserted as required from time to time.

C is an air-pipe through which air passes 50 from a suitable blowing apparatus.

C' is a branch air-pipe having valve *C*², by which air is supplied when required beneath the grate *a*, and passing up through the bed of incandescent fuel augments the heat there-of as in other gas-making apparatus of this 55 general character.

D is a case lined with fire-brick and having across it a partition, *E*, which separates the descending-flue *F* from the portion *G* of the superheater, which contains fire-brick or other refractory material, or pieces of fire-brick or other refractory material, piled up in such a manner as to allow the products of combustion or gas to pass through the same.

K is a casing connecting the generator A 65 and the superheater *D*. This also is lined with fire-brick, and there is a horizontal flue, *L*, connecting the upper part of the generator A with the descending flue *F*, and within this flue *L* is an inclined table, *M*, the lower end of which 70 is central with the middle of the flue *F*. Petroleum or other suitable hydrocarbon liquid is supplied into one or more of the pipes *O* from a suitable reservoir, the quantity being regulated by a cock, and said petroleum flows 75 upon the inclined table *M*, and is vaporized by the heat thereof, and the vapors descend through the flue *F* along with the hydrogen and other gases from the generator A. These gases commingling and being fixed by the heat 80 of the superheater pass off by the pipe *P* to any suitable holder. I place a false bottom, *Q*, in the lower part of the superheater below the flue *F* and fire-brick *G*. This false bottom becomes highly heated when the superheater is 85 being heated up, as hereinabove described, and should there be any petroleum running off the inclined table *M* and not perfectly vaporized, the same falls through the flue *F* upon this false bottom *Q*, and is there converted into vapor. 90

I find it sometimes advantageous to allow a jet of steam to pass from the pipe *R* by the cock *R'* into an annular chamber, *R*², around the upper part of the generator, so that the highly-heated steam comes into contact with the petroleum and aids in vaporizing the same. I 95 convey steam from the pipe *R* by the pipe and cock *R'* to an annular chamber, *S*, around in the wall of the generator, and from the chamber *S* a flue, *S'*, leads to the vertical tubes *S*², 100

adjacent to the flue F, so that the steam becomes highly heated by its proximity to the flues L and F, and from this flue S' the superheated steam passes by the pipe S³ to the base 5 of the generator, and ascending through the incandescent fuel is decomposed, and the resulting gases enter the flues L and F, as before mentioned. Above the partition-wall E is a bridge-wall, E², and the base of the chimney 10 or ascending-flue T passes through the case D, at some distance below the bridge-wall E². T' is a damper at the upper end of the flue T and within the chimney, the same being operated by a lever, T³, as usual.

15 When the gas-making operation is suspended, and the apparatus is to be heated up, the chimney-valve T' is opened, the supply of petroleum shut off, and the valve C² is opened to admit atmospheric air below the grate A. The 20 heat of the incandescent fuel is thus augmented and the products of combustion pass off by the flues L F and through the superheating fire-brick G. Atmosphere is admitted at the base of the superheater by the branch pipe C⁴ and 25 valve C⁵, so that carbonic oxide passing off from the fuel is consumed and the temperature of the superheater increased. The products of combustion cannot escape from the superheater until they pass over the bridge-wall E² and descend to the base of the flue T; hence there is a plenum maintained in the 30 superheater which insures the heating of the fire-brick by the flame and hot gases passing through the same.

35 It is sometimes advantageous to admit atmosphere at the pipe V, above the inclined table M, when the apparatus is being heated up. For this purpose I employ the branch air-pipe V' and cock V².

40 Man-holes W and W' are to be applied to the superheater D, as usual.

I claim as my invention—

1. The combination, in a gas-making apparatus, with the generator and superheater, of a flue, L, passing from one to the other, an inclined table, M, within said flue, and a pipe by which petroleum is supplied upon this table M, substantially as specified. 45

2. The combination, with the generator and superheater, of the flue L, passing from one to the other, the table M in the upper part of said flue, the petroleum-supply pipe at O, the steam-pipe and valve R R', and the annular chamber R², around the upper part of the generator, through which steam passes to the space above 50 the petroleum-supply table, substantially as specified. 55

3. The combination, in a superheater, of a case, a lining of fire-brick, a bridge-wall, E², in the upper part, a descending-flue, and a lateral 55 opening to the base of the chimney below the bridge-wall, for the purposes and as set forth.

4. The combination, with the generator and superheater, of the steam-supply pipe and valve R R', the annular chamber S, around the 65 generator, the flue S', below the flue L, the flue S², adjacent to the flue F, and the pipe S³, to convey the superheated steam to the base of the generator, substantially as set forth.

5. The combination, with the generator, superheater, and connecting-flue, of the descending-flue F, the false bottom Q, and the inclined table M, for the petroleum, substantially as specified. 70

Signed by me this 2d day of march, A. D. 75
1885.

THOS. F. MARTIN.
